UNITED STATES PATENT OFFICE.

REUBEN S. CLYMER, OF ALLEN TOWN, PENNSYLVANIA.

DESIGN FOR A BADGE OR EMBLEM.

No. 38,558.

Specification for Design.

Patented May 14, 1907.

Application filed April 18, 1907. Serial No. 369,036. Term of patent 14 years.

To all whom it may concern:

Be it known that I, REUBEN S. CLYMER, a citizen of the United States, residing at Allentown, in the county of Lehigh and State of Pennsylvania, have invented a new, original, and ornamental Design for a Badge or Emblem, of which the following is a specification, reference being had to the accompanying drawing, forming part thereof.

The figure is a face view of a badge or emblem showing my new design.

I claim:

The ornamental design for a badge or emblem as shown.

REUBEN S. CLYMER.
